LILLIAN H. WARD ADMINISTRATRIX OF
THE ESTATE OF JOHN D. WARD, DECEASED

BY *Murphy & Co.*
ATTORNEYS

UNITED STATES PATENT OFFICE.

JOHN D. WARD, DECEASED, LATE OF BUFFALO, NEW YORK, BY LILLIAN H. WARD,
ADMINISTRATRIX, OF BUFFALO, NEW YORK.

ADDING-MACHINE.

1,109,378.

Specification of Letters Patent.

Patented Sept. 1, 1914.

Application filed August 23, 1913. Serial No. 786,293.

To all whom it may concern:

Be it known that I, LILLIAN H. WARD, a citizen of the United States, and a resident of Buffalo, in the county of Erie and State 5 of New York, am administratrix of the estate of JOHN D. WARD, deceased, late a citizen of the United States and a resident of Buffalo, in the county of Erie and State of New York, as by reference to the original 10 letters of administration hereto annexed will more fully appear, who did in his lifetime invent certain new and useful Improvements in Adding-Machines, of which the following is a full, clear, and exact description.

15 This invention relates to improvements in adding machines, and has for an object to provide an improved simple, quick, operating structure for adding any sum desired.

Another object of the invention is to provide 20 an improved chain structure which is designed to be moved a certain distance when adding a particular number, whereby the operator can observe at all times the operation of the various parts and may know 25 whether or not the movement of the chain is correct.

A still further object of the invention is to provide 30 an adding machine with chains formed with numbered tabs and co-acting means for raising the same so as to extend substantially normal to the chain in order to be grasped and operated by the operator.

In carrying out the object of the invention 35 a suitable frame is provided in which are provided upper and lower series of sprocket wheels designed to receive an improved form of chain having numbered tags or tabs arranged thereon, together with means for raising the tabs to a position normal to the 40 chain when the tabs come opposite the front opening of the housing. In this way any particular tab may be engaged and pulled for any desired number of spaces and thus add to a given figure any number. The 45 chains are associated with means for causing a proper transfer at the right time in order that any chain operated may be freely moved for the required distance without considering whether or not a transfer is to be 50 made.

In the accompanying drawings—Figure 1 is a transverse vertical section through an embodiment of the invention, the same being taken on line 2—2 of Fig. 2; Fig. 2 is a face 55 view of an embodiment of the invention;

Fig. 3 is a sectional view through Fig. 1 approximately on line 3—3; Fig. 4 is a detailed perspective view of part of one of the number chains; Fig. 5 is a centrally vertical section through a section of one of the number chains; Fig. 6 is a detailed perspective view of one of the number tabs.

Referring to the accompanying drawings by numeral 1 indicates a base of any desired kind to which is secured a housing 2 formed of any desired material, as for instance metal. The housing 2 is provided with a face opening 3 and a series of numeral openings 4 at the top. Arranged beneath the face opening 3 is a plate 5 over which the various chains 6 are passed, as shown in Fig. 1. At the lower end of housing 2 a plurality of sprocket wheels 7 are arranged and supported by a suitable shaft 8 so as to freely rotate independently, whereby each of the chains 6 may be independently moved.

At the upper part of the housing 2 a plurality of sprocket wheels 9 are provided for accommodating the chains 6 so as to allow the same to freely move. Rigidly secured to each of the sprocket wheels 9 is a gear wheel 10 having ten teeth arranged thereon. Also rigidly secured to each of the sprocket wheels 9 is a spring catch 11 extending through an aperture 12 so as to engage one of the teeth of gear wheel 10 whenever permitted so as to transfer the motion from any particular sprocket wheel to the next succeeding wheel. Division plates or disks 13 are arranged between the gear wheel 10 and the next succeeding sprocket wheel 9 so as to normally hold the spring catch 11 out of engagement with gear wheel 10 until the spring catch 11 comes opposite the notch 14. The notch 14 is only of a sufficient length to permit catch 11 to rotate gear wheel 10 the distance of one link, and as there is only one notch 14 in the disk 13 it will require a complete revolution of the lower sprocket wheel to cause the next higher sprocket 95 wheel to be moved one tenth of a revolution. It is, of course, understood that the disks 13 are rigidly secured to shaft 15 and shaft 15 is in turn rigidly secured to the casing or housing 2 while the sprocket wheels are all 100 loosely mounted on shaft 15.

Each of the chains 6 is formed as shown in Figs. 4, 5 and 6, the same being provided with links 16 which are connected by link sections 17. Pivotedly connected with each 110

of the links 16 is a number tab 18 which is bifurcated so as to straddle part of the link connection 17 and have the depending portions 19 looped around the ends of the respective links so that the extreme end of extension 19 will form projections 20 and 21. The projections 20 and 21 are arranged to project beneath the chain, as shown in Fig. 5, when the tabs 18 are lying against the links 16. However, as the chain leaves the sprocket wheels 9 the extensions 20 and 21 engage the upper edge of plate 5 and cause the tabs 18 to be raised to a position substantially normal to the chain and remain in that position until the chain moves off of the plate 5. This provides handholes for an operator whereby the operator may freely and quickly move any chain desired for any desired distance.

Arranged on the plate 5 are numbers which appear through the links 16, as clearly shown in Fig. 2, so as to guide a person in moving the chain, whereby the chain may be moved any desired distance, as for instance, six spaces, one space, or any other number of spaces, according to the number designed to be added to the numbers in openings 4. It will be observed that the tabs 18 are lying flat against the chain when they appear opposite openings 4, but as soon as they move therefrom they are raised to an upstanding position. If it is desired to add four to the units column shown in Fig. 2 any of the tabs 18 are grasped and pulled for four spaces, whereupon the numeral six will appear in the first opening of the series of

openings 4. If numeral 6 was to appear in the opening 4 instead of the numeral 2 and the units chain was pulled five spaces the numeral 1 would appear in the first opening and the catch 11 would cause the tens wheel to rotate one tenth of a revolution and therefore advance the second or tens chain one number.

Having thus described my invention what I claim as new and desire to secure by Letters Patent is—

In an adding machine of the class described, a casing formed with a row of openings, a sprocket wheel arranged in said casing so that part of the same will appear opposite said openings, a chain for each of said sprocket wheels, a pivotally mounted number tab on each of said chains designed to be brought successively past said openings, each of said tabs being formed with a projection and means in said housing engaging said projections for moving the tabs to a position substantially normal to the links after the links have passed said row of openings, whereby said tabs may be grasped and said chains moved to any desired extent.

In testimony whereof I have signed my name to this specification in the presence of two subscribing witnesses.

LILLIAN H. WARD,
As administratrix of the estate of John D. Ward, deceased.
